(57) **CLAIM**

The ornamental design for hydration bladder, as shown and described.

DESCRIPTION

FIG. 1 is a front perspective view of hydration bladder illustrating our new design in an unfilled state;
FIG. 2 is a front elevation view thereof;
FIG. 3 is a back elevation view thereof;
FIG. 4 is a left side elevation view thereof;
FIG. 5 is a right side elevation view thereof;
FIG. 6 is a top plan view thereof;
FIG. 7 is a bottom plan view thereof;
FIG. 8 is a front perspective view of hydration bladder illustrating our new design in a filled state;
FIG. 9 is a front elevation view thereof;
FIG. 10 is a back elevation view thereof;
FIG. 11 is a left side elevation view thereof;
FIG. 12 is a right side elevation view thereof;
FIG. 13 is a top plan view thereof; and,
FIG. 14 is a bottom plan view thereof.

The broken lines in the drawing views represent unclaimed portions of hydration bladder which are included for the purpose of illustrating unclaimed environment only, and form no part of the claimed design.
